Primary Examiner — Ramzi Almatrahi*(74) Attorney, Agent, or Firm* — Venable LLP**(57) CLAIM**

The ornamental design for an interchangeable lens for camera, as shown and described.

DESCRIPTION

FIG. 1 is a front elevation view of an interchangeable lens for camera showing our new design;

FIG. 2 is a back elevation view thereof;

FIG. 3 is a top plan view thereof;

FIG. 4 is a bottom plan view thereof;

FIG. 5 is a left side elevation view thereof;

FIG. 6 is a right side elevation view thereof; and,

FIG. 7 is a front perspective view thereof.

The broken lines depict portions of the interchangeable lens for camera in which the design is embodied that form no part of the claimed design.
